UNITED STATES PATENT OFFICE.

JACOB H. WEISBROD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR-UNDERFRAME.

1,183,932. Specification of Letters Patent. Patented May 23, 1916.

Application filed March 31, 1914. Serial No. 828,522.

To all whom it may concern:

Be it known that I, JACOB H. WEISBROD, residing at St. Louis, Missouri, and being a citizen of the United States, have invented 5 certain new and useful Improvements in Car-Underframes, of which the following is a full, clear, and exact description, such as will enable others skilled in the art to which it appertains to make and to use the same, 10 reference being had to the accompanying drawings, which illustrate the preferred form of the invention; though it is to be understood that the invention is not limited to the exact details of construction shown 15 and described, as it is obvious that various modifications thereof will occur to persons skilled in the art.

This invention relates broadly to car underframe construction and more particularly to a combined draft and center sill connection.

The principal object of the invention is to provide means for the ready assembling with the center sill and draft members of 25 either one piece bolsters, or bolsters having some of their parts separable.

Another object of this invention is to provide a device for connecting the draft members and center sill in such manner as 30 to provide a very strong framing member extending from one end of the car to the other.

A still further object of this invention is to provide a connection between the draft 35 members and the center sill in such manner that the connected parts constitute a sectional center sill extending from one end of the car to the other, and of such construction that a portion of said connection serves as a 40 filler for the bolster assembled therewith.

Other and further objects of this invention will in part be obvious and will in part be pointed out in the specification herein-after following by reference to the accompanying drawings in which like parts are 45 designated by like characters throughout the several views thereof.

Figure 1 is a plan view of a portion of a car underframe embodying one adaptation of my invention. Fig. 2 is a vertical section taken in front of the bolster and through the draft and center sill connection along the longitudinal center of the bolster, on line 2-2, Fig. 1, and looking in the direction of the arrow. Fig. 3 is an enlarged plan view of the connection and shows the

draft members, center sill, and bolster assembled therewith. Fig. 4 is a side elevation of the parts shown in Fig. 3, showing the bolster in transverse section. Fig. 5 is a vertical section through the draft members 60 and shows the front end of the connection. Fig. 6 is a similar section through the center sill and shows the rear end of the connection. Fig. 7 is a vertical section through the connection and bolster taken on line 65 7-7 of Fig. 4. Fig. 8 is a vertical section taken longitudinally through the center of the connection. Fig. 9 is a view taken in front of the bolster and showing the connection modified for assembly with a bolster 70 having an integral top member. Fig. 10 is a plan view of the parts illustrated in Fig. 9 and showing a portion of the connection and draft members broken away. Fig. 11

is a side elevation of the parts illustrated in Figs. 9 and 10, showing the bolster in vertical cross section and in position within the open slot of the connection. Fig. 12 is a perspective view showing the open slotted 75 connection illustrated in Figs. 9, 10 and 11. Fig. 13 shows the central portion of one 80 form of a one-piece bolster adapted to the invention. Fig. 14 is a plan view of a further embodiment of my invention in which the connection is formed of more than 85 one part. Fig. 15 is a side elevation of the parts illustrated in Fig. 14, and showing a portion of the bolster in vertical cross section. Fig. 16 is a longitudinal vertical section through the center of the divided connection illustrated in Figs. 14 and 15. Fig. 17 is a vertical section taken through the draft members on line 17-17 of Fig. 15, and looking in the direction of the arrows. Fig. 18 is a vertical section through the center sill and taken on line 18-18 of Fig. 15, 90 looking in the direction of the arrows. Fig. 19 is a perspective view of the upper and lower portions constituting a form of the connection when made of a plurality of 95 parts.

Referring to the drawings and more particularly to Figs. 1 to 8 inclusive, the construction is illustrated as accommodating a bolster arranged in a plane below the top of the connection so as to provide a support for continuous floor stringers, and includes a center sill 1, which extends approximately the full distance between the bolsters and may comprise an I-beam or other suitable 100 construction. The draft sills 2, which pref-

erably are connected by a plate 3 secured to the upper flanges thereof, are united to the center sill by means of a connection 4 in such manner as to substantially constitute 5 the draft sills, and the center sill as a single unitary structure formed of sections. The connection 4 co-operates with a bolster 5 which may be of the one-piece type, as shown in Figs. 9, 10, 13 and others, or built 10 up of a plurality of parts, as is shown in Figs. 1, 2, 3, 4 and 7. For co-operation with the built up type of bolster, the connection is provided with an opening 6, through which the cover plate 7 of the bolster passes. 15 This cover plate 7 being riveted to the upper flanges of the bolster member serves to unify the bolster structure. In order to provide a very rigid and secure attachment to the center sill, the connection 4 is provided 20 with rearwardly projecting wings 8, which lap the ends of the center sill 1 and are disposed in and substantially fill the space between the top and bottom flanges 9 and 10 thereof. In order to further 25 strength in the wings 8, they may be provided with outstanding triangular shaped ribs 11 arranged substantially horizontally, and the wings 8 are preferably secured to the center sill 1 by means of rivets passing 30 through the web thereof and being located in rows between the said ribs. Forwardly of the rear wall 12 to which the wings 8 of the connection are joined, the connection in vertical cross section, is substantially box- 35 shape, being divided at the bolster by the opening 6 and extending forward of the bolster for connections to the draft members 2. The draft members 2 are secured to the side walls 14 of the connection 4 and to the shelves 15, which project outwardly from the lower edges of the respective side walls. The opening 6 may be arbitrarily considered as dividing the connection at the bolster into upper and lower sections 16 and 17 respectively; the lower section 17 being positioned 40 within the bolster including the center bearing 18 to the cover plate 7 and constitutes a filler for the bolster; and the upper section 16 being above the bolster constitutes a bridge between the rear wall 12 and the front wall 19. The structure described thus provides a draft and center sill connection of sufficient sectional area at all 45 points within and above the bolster to transmit directly to the center sill 1 all stresses set up in the draft members 2.

One form of construction adapted to be used in connection with a one-piece type of bolster having an integral upper member, as 50 shown in Fig. 13, is illustrated in Figs. 9 to 12 inclusive, wherein the connection is shown as being provided with an open slot 20. A portion of this slot as at 21, is relatively narrow, being only of a width sufficient 55 to permit the passage of the upper

or tension member 22 of the bolster. In order to facilitate the proper seating or securing of the bolster within the connection, the upper edge of the slot 21 is preferably below the position to be occupied by the upper surface of the bolster when it is finally secured in the connection, and therefore the narrow slot 21 leads to a larger opening 24 which provides bearing shoulders 25 for the upper member 22 of the bolster. Except 70 for the open-ended slot and the one-piece bolster, the construction illustrated in Figs. 9 to 13 inclusive is substantially the same as the construction illustrated in Figs. 1 to 8 inclusive.

In order to facilitate repairs it may be found desirable at times to form the connection of two parts as is illustrated in Figs. 14 to 19 inclusive, wherein the connection is shown as comprising an upper, or bridge, 85 section 26 and a lower, or bolster, center-filler casting section 27. The upper section 26 carries a wing member 28 and the lower member 27 carries a complementary wing member 29, and the upper and lower sections 26 and 27 are respectively provided with engaging shoulders 30 and 31.

Except for slight variations necessarily due to the construction of the different embodiments of the connection, the several 90 parts are assembled, in each case, in a similar manner, and therefore it is believed to be only necessary to describe the assembling of one embodiment, for example, an assembly including the divided connection. 100 In assembling this construction it is preferable that the sections 26 and 27 be first secured to the end of the center sill 1 by rivets 32 passing through the wings 28 and 29 and through the web 34 of the center sill. The forward portions of the sections 26 and 105 27 are kept in proper spaced relationship by means of the engaging shoulders 30 and 31, and the inset portion 35 provides an enlarged opening analogous to the opening 24 in the open end unitary connection illustrated in Figs. 9 to 12. The bolster upper member 22 is passed within the narrow opening 21 and is nested between the bearing shoulders 25 and the upper section 26. The bolster when in position within the slot is secured against displacement by means of rivets 36 passed through the side wall 37 of the section 27 and the bolster flanges 38. The draft members 2 are then secured to the 110 sections 26 and 27 by means of the rows of rivets 39 passing through the side walls 40 of the upper member 26 and the side walls 37 of the lower member 27.

My invention may obviously be embodied 115 in other and further specific constructions without departure, and therefore the specific constructions of preferred forms here shown and described, are to be considered as illustrative and not in a limiting sense.

Having thus described my invention, what I desire to claim is:

1. In a car underframe, the combination with a single beam center sill; draft sills spaced apart from said center sill; a bolster; and a connection extending between said draft sills and said center sill, said connection including a forward portion having a width equal to the distance between the draft sills; an intermediate portion having a part extending through and a part above said bolster, and a triangular formed rear portion provided with a slot to receive the web of the center sill. 70
2. In a car underframe, the combination with a single beam center sill; draft sills; and a bolster; of a single connection comprising a box-like forward portion, a triangular shaped rear portion, and an intermediate portion extending across and between parts of the bolster, the said rear portion being slotted to lap the end of said center sill. 75
3. In a car underframe, the combination of a single beam center sill; draft sills; and a bolster; of a connection co-operating with all previous mentioned parts, said connection including a forward box-like portion extending into said bolster, and a rearward portion provided with wings adapted to lap the web of the center sill. 80
4. In a car underframe, the combination of a single beam center sill; a bolster; draft sills; and a connection between said center sill and said draft sills, said connection including a bridge over said bolster and a compression portion passing through said bolster and forming a filler therefor. 85
5. In a car underframe, the combination of a single I-beam center sill; draft sills; a bolster located between the end of said center sill and said draft sills; and a connection extending between said draft sills and said center sills, said connection including wings lapping the end of said center sill, a box-like portion lapping the ends of said draft sills, and an intermediate portion including a bridge above the bolster and a filler extending across and between parts of the bolster. 90
6. In a car underframe, the combination with a single center sill; draft sills; a bolster; and a connection between said draft sills and said center sill, said connection being provided with vertical wings having thereon triangular horizontal webs, and provided with an opening for the passage of a portion of said bolster, the part above said opening comprising a bridge and the part beneath said opening comprising a filler for the bolster diaphragms. 95
7. In a car underframe, the combination with a single beam center sill; draft sills spaced apart from said center sill; a bolster crossing between said center sill and said draft sills and below the upper surface of said sills; and a connection between said draft sills and said center sill, said connection extending above said bolster and between parts of the bolster. 100
8. In a car underframe, the combination with a single beam center sill; draft sills spaced apart from said center sill; a bolster; and a connection extending between said draft sills and said center sill, said connection including a forward portion having a width equal to the distance between the draft sills; an intermediate portion having a part extending through and a part above said bolster, and a triangular formed rear portion provided with a slot to receive the web of the center sill. 105
9. In a car underframe, the combination of a single I-beam center sill; draft sills; a bolster crossing between said center sill and said draft sills and below the upper surface of said sills; and a connection connecting said draft sills and said center sill and constituting the compression member for the bolster and a seat for the center bearing. 110
10. In a car underframe, the combination of a single beam center sill, spaced apart draft sills, a bolster extending across the ends of said center sill and the ends of said draft sills, and a connection having a part extending below the upper part of said bolster, said connection carrying said draft sills, and connecting said bolster and said center sill. 115
11. In a car underframe, a continuous member extending from one end of the car to the other comprising draft sills, a single beam center sill, and connections intermediate said draft sills and said center sill, said connections being provided with openings to permit the passage of the tension member of the bolster and forming also a compression member within said bolster. 120
12. In a car underframe, the combination of a center sill; spaced-apart draft sills; and a connection, said connection having side walls lapping the ends of the draft sills and extending rearwardly through the bolster and connecting with a rear wall, said side walls being provided with openings to receive a bolster part, and wings extending rearwardly from said rear wall and adapted to lap the end of said center sill. 125
13. In a car underframe, the combination of draft sills; a center sill spaced apart from said draft sills; a bolster arranged at right angles to the axis of said sills and passing between the ends of said sills; and a connection partly within said bolster and lapping said draft sills and said center sill, said connection including a box-like portion provided with an opening to permit the passage of a part of said bolster, said box-like portion being provided with transverse horizontal and vertical ribs, one of said vertical ribs comprising a front wall adjacent said opening and another of said ribs comprising a rear wall also adjacent said opening, and wings extending from said rear wall and lapping the ends of the center sill. 130

14. As an article of manufacture, a connection between a single beam center sill and spaced apart draft sills, including a forward box-like portion provided with an opening between its upper and lower portions for the passage of the tension member of a bolster, a vertical wall to the rear of said opening, a pair of complementary wings provided with reinforcing ribs spaced apart and adapted to lap the end of the center sill and to be secured thereto.

15. As a new article of manufacture a connector for a single center sill and spaced draft sills, consisting of a pair of vertically separable castings adapted for connection with each of said sills.

In witness whereof I have hereunto set my hand in the presence of two witnesses.

JACOB H. WEISBROD.
